COMBINED CIGARETTE VENDING MACHINE AND AUTOMATIC PHONOGRAPH

Frank Realmuto, Bayside, N.Y., and Jerome J. Columbo,
Boston, Mass., assignors to Command Industries
Corp., Boston, Mass.

Filed Jan. 12, 1961, Ser. No. 63,515

Term of patent 14 years

(Cl. D56—4)

FIG. 1

FIG. 2

FIG. 3

FIG. 4

FIG. 1 is a front elevational view of a combined cigarette vending machine and automatic phonograph embodying our new design:

FIG. 2 is a side elevational view;

FIG. 3 is a rear elevational view; and

FIG. 4 is a front perspective view thereof.

We claim:

The ornamental design for a combined cigarette vending machine and automatic phonograph, as shown.
